BUILDING

George B. Brown, Kansas City, Mo.

Application September 29, 1947, Serial No. 141,650

Term of patent 7 years

(Cl. D13—1)

To all whom it may concern:

Be it known that I, George B. Brown, a citizen of the United States, residing at Kansas City, Missouri, in the county of Jackson and State of Missouri, have invented a new, original, and ornamental Design for a Building, of which the following is a specification, reference being had to the accompanying drawing, forming a part thereof.

Figure 1 is a perspective view of a building showing my new design.

Fig. 2 is a side elevational view thereof.

Fig. 3 is a top plan view thereof;

Fig. 4 is a front elevational view thereof; and

Fig. 5 is a rear elevational view thereof.

I claim:

The ornamental design for a building, as shown.
GEORGE B. BROWN.
